ELECTRICAL CONNECTOR

John A. Korengold, Chicago, Ill.

Application December 22, 1937, Serial No. 181,071

3 Claims. (Cl. 173—328)

This invention relates in general to electrical connectors and has for its primary objects the provision of an electrical connector which may be readily pulled apart and reconnected with exceptional ease and facility; which, when connected, provides an unusually rigid, low resistance, and satisfactory contact; which may be quickly and conveniently attached to the respective electrical conductors joined by it; which may, if desired, be rendered explosion proof; which is very rugged and durable; and which is otherwise highly satisfactory and efficient in the performance of its intended functions.

And with the above and other objects in view, my invention resides in the novel features of form, construction, arrangement, and combination of the several parts presently described and pointed out in the claims.

In the accompanying drawing—

Figure 1 is a longitudinal sectional view of an electrical connector, constructed in accordance with and embodying my present invention, illustrating the use of such a connector in a conduit pipe;

Figure 2 is a top plan view of the female portion of the connector;

Figure 3 is a top plan view of the female portion of the connector with the contact posts thereof removed;

Figure 4 is a diametral sectional view of the female connector member, taken approximately along the line 4—4, Figure 2;

Figure 5 is a fragmentary sectional view of the female connector member, taken approximately along the line 5—5, Figure 2;

Figure 6 is a top plan view of the male member of the connector;

Figure 7 is a diametral sectional view of the male connector member, taken approximately along the line 7—7, Figure 6; and

Figure 8 is a fragmentary sectional view of the male connector member, taken approximately along the line 8—8, Figure 6.

Referring now in more detail and by reference characters to the drawing, A designates a section of conduit member having an externally threaded end 1 and being interiorly provided with a preferably integrally formed annular shoulder 2 spaced inwardly from the threaded end in the formation of a connector-receiving socket 3. B designates a companion conduit member, diametrically enlarged for a predetermined distance inwardly from its one end in the provision of a connector-receiving socket 4 for endwise abutting engagement with the conduit member A and

having, at its rearwardly presented end, an annular abutment face 5 for abuttingly engaging the annular flange 6 of the union-collar C, which, in turn, is internally threaded for conduit-connecting engagement with the threaded end 1 of 5 the conduit member A.

Formed preferably of molded "Bakelite," hard rubber, or other suitable dielectric material for snug-fitting removable disposition within the connector-socket 3, is a female connector member 7 including a cylindrical shank portion 8 provided with a pair of axial bores 9 and a pair of tapped plugs 10, preferably formed of electrically conductive material and molded into or otherwise rigidly mounted in the shank portion 8, the shank portion 8 being of external diametrical size substantially equivalent to the internal diametrical size of the annular shoulder 2 of the conduit member A. Formed preferably integrally with, and extending axially outwardly from, the inner face 1 of the shank 8, is a diametrically enlarged cup-like member 11, being in external dimensions substantially equal to the corresponding dimensions of the connector-receiving socket 3.

Provided for threadedly removable disposition in the tapped plugs 10, is a pair of female connector posts 12 each diametrically enlarged and bored at one end in the provision of an axially extending cup-like portion 13, the side wall of which is provided with a plurality of lengthwise slots 14, the rearward end of the cup-like portion 13 being exteriorly faced off in the provision of a flat annular abutment margin 15, all for purposes presently more fully appearing and 35 as best seen in Figures 1 and 4.

Likewise formed preferably of molded Bakelite, hard rubber, or other suitable dielectric substance, is a male connector member 16, including a shank portion 17 of diametrical size and length 40 substantially equivalent to the corresponding inner dimensions of the connector-receiving socket 4 for snug fitting disposition therein, the male connector member 16 further including a plug portion formed integrally with and projecting 45 outwardly from the shank portion 17, being diametrically sized to fit snugly within the cup-like portion 11 of the female member 7 and being in length considerably shorter than the depth of the cup-like portion 11 so as to avoid abutment 50 with the outwardly presented margins of the female posts 12 thereof, whereby to permit the male member 16 to be inserted within the female member, as best seen in Figure 1.

Formed in and extending through the shank 55

portion 17 of the male connector member 16, is a pair of parallel apertures 18 preferably arranged in diametral juxtaposition. Rigidly mounted also in the shank portion 17 of the male connector member 16, is a pair of parallel cylindrical metallic insert members 19 preferably arranged in diametral juxtaposition, being on their upper face preferably flush with the upper face f' of the shank portion 17 and having an internally threaded bore 20 for receiving the threaded end of a connector post 21 diametrically sized for snug-fitting engagement within one of the female connector posts 12. It will, of course, be apparent in this connection that the bores 20 will be axially aligned with the respective female connector posts 12, so that the male connector posts 21 will readily fit thereinto as the male and female connector members are put together. The shank portion 17 of the male connector members 16 is provided with an axially disposed radial slot 22, which extends diametrically across and through the metallic insert member 19 and is of a depth equal to the length of the bore 20 thereof, all for purposes presently more fully appearing and as best seen in Figures 7 and 8.

In use, the selected conductor wires are suitably bared at their ends in the conventional manner and inserted upwardly through the apertures 9 of the female connector member 7. Flat conductor rings r of conventional design are soldered to the bared ends and are bent over into flatwise abutment with the respective tapped plugs 10. The female connector post members 12 are thereupon threaded into the tapped plugs downwardly into tight engagement with the upwardly presented faces of the connector rings r whereby to hold them rigidly in electrically conductive engagement, as best seen in Figures 4 and 5. 40 The other electrical connectors or leads, which are to be brought into circuit-completing connection with the previously mentioned conductors or leads, are likewise bared at their ends in the conventional manner and inserted upwardly 45 through the apertures 18 of the male connector plug member. The bared ends are then bent over at right angles into the slot 22, so that they will respectively extend along the bottoms and across the bore 20 of the metallic insert members 19. The male connector post 21 is thereupon threaded into the bore 20 and screwed down into tight engagement with the bared end of the connector wires for electrically conductive and gripping engagement therewith, as best seen 55 in Figures 7 and 8.

The male and female connector plug members are then inserted into each other in such a manner that the male connector posts 21 will respectively be inserted axially into the female connector post members 12 for circuit completing engagement therewith substantially in the manner shown in Figure 1. It will, of course, be apparent that, as the respective contact members slide into each other, the effect of a so-called 60 "wiping" contact will be achieved over the entire contact area, with a resulting high contact efficiency.

If desired, the apertures 9 and 18, respectively, of the male and female connector members may 70 be sealed with a suitable plastic substance in order to provide a substantially gas-tight or explosion-proof electrical connection joint. In the case of the use of the present electrical connector in conjunction with a conduit pipe, as illustrated 75 in Figure 1, the joined connector members are

then placed into the respective ends of the conduit members A and B, as shown in Figure 1, and the threaded collar C turned into conduit-connecting position, whereupon the male and female members, respectively, will be held tightly 5 within each other.

It should be pointed out in this connection that in various types of electrical apparatus, such as the conduit pipes A and B, the mechanical connection of the parts requires a certain amount 10 of axial movement or play. The present connector member provides a considerable amount of such axial freedom, the male connector posts merely slipping axially within the female connector posts to a greater or lesser degree as may 15 be desired in the mechanical connection of the housing parts, such as the conduit pipes A and B.

Thus by my present invention I have provided an electrical connector which is exceptionally simple in construction and operation and provides a highly efficient detachable connection, which, when joined to complete the electrical circuit, does so in a sort of wiping manner which provides unusually efficient contact. My present invention further provides a connector member 25 which is readily disconnected, so that the various housing elements may be disconnected without the necessity of extensive rewiring operations. Suppose, for instance, that the conduit pipe A carried at its one end a lamp socket and shade 30 and the conduit B at its other end was connected to the stand, base, or other supporting structure of the lamp. In such a case, as will readily be apparent, if the lamp socket became damaged, it could be readily removed from the base structure for repair without completely dismantling the entire structure and disconnecting all the wires.

Since the most common type of electrical installation is the two-wire system, the application of the present invention to such a two-wire system is illustrated, although it should be understood that the present invention is equally well applicable to different types of electrical systems, such as three-wire systems, for instance, 40 by the mere multiplication of parts in a manner readily apparent to those skilled in the art.

It should be understood that changes and modifications in the form, construction, arrangement, and combination of the several parts of the 50 electrical connector may be made and substituted for those herein shown and described without departing from the nature and principle of my invention.

Having thus described my invention, what I 55 claim and desire to secure by Letters Patent is—

1. An electrical connector element comprising a dielectric base having an aperture whereby an electrical wire may be inserted through the base, an internally threaded cup set into the base, and a contactor member having at one end a jack-post receiving socket and at its other end a screw-post for threaded engagement in the cup, said contactor member being enlarged adjacent the inner end of its screw-post in the provision 60 of an abutment shoulder for contactively engaging, and at the same time retentively holding, the electrical wire.

2. An electrical connector element comprising a dielectric base having an aperture whereby an 70 electrical wire having a non-insulated end may be inserted through the base with its non-insulated end bent over upon the base, an internally threaded cup set into the base and having an outwardly presented flat annular rim, and a con- 75

- 5 tacter member having at one end a conductor-receiving substantially cylindrical and concentric socket and at its other end a screw-post for threaded engagement in the cup, said contactor member being enlarged adjacent the inner end of its screw-post in the provision of an abutment shoulder in opposing relation to the cup-rim for contactively engaging the bent-over non-insulated end of the electrical wire and retentively holding said wire-end against the cup-rim.
- 10 3. An electrical connector element including a dielectric base member provided with a shank having an outwardly presented face, an internally threaded cylindrical cup set into the shank and opening upon the shank face, said dielectric member being provided with an aperture extend-
- 15 ing axially therethrough adjacent said cup, said shank and said cup being provided with a narrow slot extending diametrically across the cup and opening at one end into the aperture and at the other end upon the outer side face of the shank, 5 said slot being substantially flush along its bottom face with the inside bottom face of the cup, and a jack-post member having a threaded end portion substantially greater in length than the depth of the cup for co-operative engagement in 10 the cup whereby to force a bent-over section of conductor wire over into the slot and downwardly against the inside bottom wall of the cup for simultaneously making contact therewith and retentively holding the same in place. 15
